UNITED STATES PATENT OFFICE.

DOYLE W. McCULLOCH, OF BLACKWELL, OKLAHOMA.

OIL BURNER.

Application filed March 14, 1923. Serial No. 625,026.

To all whom it may concern:

Be it known that I, DOYLE W. McCULLOCH, a citizen of the United States, residing at Blackwell, in the county of Kay and 5 State of Oklahoma, have invented certain new and useful Improvements in Oil Burners, of which the following is a specification.

This invention relates to oil burners and has for its object the provision of a simple 10 easily adjusted device which may be readily applied to any stove and by the use of which any form of liquid fuel may be burnt without waste. The invention is illustrated in the accompanying drawing and will be 15 hereinafter fully set forth.

In the drawing:

Figure 1 is a perspective view of a burner embodying my invention showing the same as arranged for use;

20 Fig. 2 is a central vertical section through the burner, and

Fig. 3 is a horizontal section on the line 3—3 of Fig. 2.

In carrying out my invention, I employ 25 a bracket or collar 1 which may be bolted upon any internal projection or stationary part of a stove and through this collar is fitted a pipe 2 which is adjustably held in the collar by a set screw 3 mounted in the 30 latter and bearing upon the pipe. The ends of this pipe are open and arranged concentrically therein is an inner pipe 4 which is relatively of small diameter, the inner pipe projecting through and above the upper 35 end of the outer pipe and having a cap or damper 5 secured thereon by a set screw 6. The damper cap may be secured in place so as to bear directly upon the upper end of the outer pipe 2 or it may be spaced any desired 40 distance therefrom in an obvious manner and the flow of heated currents through the pipe may be thus regulated. To maintain the proper relation of the inner pipe to the outer pipe and secure it therein I provide 45 stationary pins or studs 7 which are fixed in the wall of the outer pipe and are adapted to bear against the inner pipe and constitute rests for the same, as will be readily understood upon reference to Fig. 50 3. Coacting with these pins or rests 7, set screws 8 are mounted in the wall of the outer pipe and adapted to bear against the inner pipe so that the said inner pipe will be clamped against the rests or pins 7 when 55 the set screws are turned home. I also em-

ploy a retarding element 9 which is preferably composed of two strands of wire twisted together, as clearly shown, and having their upper extremities bent laterally, as shown at 10, so as to rest upon the upper end of the inner pipe when in use and be thereby supported. The oil or other liquid fuel is supplied to the burner through a feed pipe 11 equipped with a regulating or cut-off valve 12 whereby the flow of the fuel may be easily 15 adjusted, the said valve being so arranged that the fuel issuing therefrom will drop onto the wick 9 or into the bore of the inner pipe 4. Below the pipes 2 and 4 and spaced therefrom but in axial alinement therewith 20 is a splash plate 13 having a circular rib 14 upon its upper surface, the under surface of said plate being provided with a rim 15 so that the plate may rest upon a grate having a raised center and clear the raised portion. 25

The burner may be arranged within any heating stove, the splash plate being placed upon the grate of the stove and the pipes or concentric burner tubes being supported vertically within the fire-box of the stove 30 above the splash plate, while the supply pipe and regulating valve may be supported in any convenient or preferred manner within the stove so as to discharge the fuel as desired. Initially, a small supply of the fuel 35 is permitted to flow onto the splash plate, and this fuel is ignited so that the resulting flame will play upon the ends of the pipes and heat the same so that fuel subsequently fed to the burner tubes will be quickly 40 vaporized and will ignite at once as it issues in the form of vapor from the lower end of the inner pipe. The outer pipe provides for the admission of air to the flame and a circulation of air about and through the tubes 45 which will prevent overheating and consequent warping or cracking of the tubes while at the same time sufficient heat will be retained therein to facilitate the vaporization 50 of the fuel. The flame, of course, will play upon and about the splash plate which will quickly be raised in temperature, and it will, therefore, preferably be constructed of some refractory material so that it will prove durable notwithstanding the high temperatures 55 to which it is subjected. The heating of this plate will, of course, aid in instantly vaporizing the liquid fuel which may pass from the burner tubes in the liquid state so that 60 the combustion will be complete and there 65

will be very little, if any, deposit of soot or other carbon. Actual use of the device by me has shown that, if the device be properly adjusted, the combustion will be perfect and no carbon will be deposited. The wick holds the fuel to the sides of the pipe so that flow will be retarded and the oil or other fuel will flow down the wall of the tube in a very small volume. Should a hotter fire be desired, the wick may be raised and will then obstruct the flow through a shorter length of the inner tube and the oil may flow with greater rapidity so that the flame at the hot plate will be fed faster and will thereby be maintained in a more intense state.

Having thus described the invention, what is claimed as new is:

A liquid fuel burner comprising concentric open-ended burner tubes, spaced rests 20 within the outer tube bearing against the inner tube, securing members mounted in the wall of the outer tube and engaging the inner tube and cooperating with the rests to secure the inner tube in place, a splash plate 25 disposed below and in spaced relation to and in axial alinement with the burner tubes, and means for supplying fuel to the inner burner tube at the upper end of the same.

In testimony whereof I affix my signature.

DOYLE W. McCULLOCH. [L.S.]
